Attorneys

UNITED STATES PATENT OFFICE.

JAMES MCMILLAN, JR., OF PIEDMONT, WEST VIRGINIA.

TOBACCO PIPE.

Application filed September 20, 1922. Serial No. 591,522.

To all whom it may concern:

Be it known that I, JAMES MCMILLAN, JR., a citizen of the United States, and resident of Piedmont, in the county of Mineral and

5 State of West Virginia, have invented certain new and useful Improvements in Tobacco Pipes, of which the following is a full, clear, and exact description.

10 My invention relates to smoking pipes generally, and has for its object to provide a simple and ornamental attachment therefor which conducts off a portion of the heat and thus materially cools the smoke before arriving at the end of the pipe stem.

15 Another object of the invention is the provision of a well in the pipe stem and means for causing a portion of the nicotine sorghum and moisture to collect in the well.

Another object of the invention resides in 20 the provision of an auxiliary air inlet to the pipe stem at a point above the well which not only cools the smoke, but also has a tendency to retain the nicotine, etc., in the bottom of the well, due to the current of air 25 pressing on the top of the collected matter.

A further object of the invention comprises an arrangement of spring fingers which, in addition to collecting nicotine and the like, also frictionally engage the wall of 30 the well and thereby secure the plug in place.

Other objects and advantages of the invention will be apparent from the following description when taken in connection with 35 the accompanying drawings, in which:

Figure 1 is a longitudinal section through a tobacco pipe.

Figure 2 is a horizontal section taken on line 2-2 of Figure 1.

40 Figure 3 is a bottom plan view of the detachable plug.

Figure 4 is an enlarged fragmentary section taken through the pipe stem, and

45 Figure 5 is a section through a modified form of the device.

Referring to the drawing more in detail, the numeral 1 designates the bowl of a tobacco pipe provided with a stem 2. This stem is formed with a well 3 which extends 50 below the bore 4 of the stem and is provided with a metal or other wear-resisting lining 5. This well is for the purpose of receiving a portion of the nicotine, sorghum, moisture and the like which may be collected from the 55 smoke by the device described hereinafter.

In order to diffuse the smoke, lower the temperature thereof and generally improve its hygienic properties, as well as its taste, I have provided the plug 6, which is formed with the interrupted threads 7 and carries 60 an annular row of downwardly extending metal pins 8 attached to its lower end. Mounted on the top of the plug 6 is a serpent 9 having an air passage 10 extending throughout its length and communicating 65 with the conduit 11 extending through the plug 6. While for the purpose of illustration I have shown a serpent attached to the plug 6, it is obvious that any other ornamental device having an opening therein 70 may be substituted.

The plug just described is adapted to be screwed or otherwise attached to the pipe stem by seating the same in an opening 12 formed in the upper wall of the stem in 75 line with the well 3. When so seated in the opening 12 the plug is held against accidental displacement by means of the pins 8 which frictionally engage the lining 5 of the well.

In operation, the smoke passing through 80 the bore 4 is diffused by the pins 8, which also collect a portion of the nicotine, sorghum, etc., from the smoke and direct the same to the well 3. The pins 8, in connection with the metal plug 6 and metal projection 9, also act as a radiator in conducting a portion of the heat to the exterior of the pipe stem. The air inlet 10 communicates with the conduit 11 and allows an auxiliary 85 supply of air to be combined with the smoke in the stem, thereby further cooling and diluting the smoke. Furthermore, the stream of air descending through the conduit 11 aids the pins 8 in holding the 90 material collected in the well 3 in place and prevent the same from being drawn through the mouth piece 13. The well and plug 95 may be cleaned, of course, by merely removing the latter from the stem which gives 100 complete access to the well 3.

In the modified form of the invention shown in Fig. 5 the plug 6 is provided with the same longitudinal conduit 11, but instead of the annular row of pins 8 the 105 modified plug carries the annular row of coil springs 14. These springs are more effective in diffusing the smoke and in collecting objectionable matter therefrom. A metal disc 15 is carried by the lower ends 110

of the springs and prevents the latter from mutilating the pipe stem when the plug is attached and removed. This disc is used in lieu of the lining 5 and in conjunction with 5 springs 14 will prevent accidental turning movement of the plug. An aperture 16 is formed in the disc 15 to permit the insertion of a tool for cleaning the conduit 11.

From the foregoing description it will be 10 seen that I have provided an extremely simple attachment for tobacco pipes which functions not only as a radiator, but also removes a portion of the nicotine, sorghum, etc., from the smoke and otherwise improves 15 its taste.

In accordance with the patent statutes, I have described what I now believe to be the best embodiment of the invention, but I do not wish to be understood thereby as 20 limiting myself or the scope of the invention, as many changes and modifications may be made without departing from the spirit of the invention; all such I aim to include in the scope of the appended claims.

25 What I claim as new and desire to secure by Letters Patent is:

1. A tobacco pipe having a lateral opening in its stem, said stem having a well therein in alignment with said opening, the bottom of the well being positioned below 30 the bore of the stem, a plug in said lateral opening, and a plurality of spring wires secured to said plug and adapted to collect moisture, nicotine and the like and direct the same to the well. 35

2. A tobacco pipe having a lateral opening in its stem, a plug of heat conducting material positioned in said opening, and elongated members of heat-conducting material attached to the top and bottom of 40 the plug, said lower member bridging the bore of the stem.

3. A plug for tobacco pipes including a plurality of spring wires secured to the base of the plug and adapted to collect moisture, 45 nicotine and the like.

4. A plug for tobacco pipes including a plurality of wires secured to the base of the plug and an air conduit attached to the top of the plug.

JAMES McMILLAN, JR.
